(57) **CLAIM**

The ornamental design for a vehicle door lock, as shown and described.

DESCRIPTION

FIG. 1 is a front view of a vehicle door lock of the present invention when the vehicle door lock is in a closed configuration.

The rear view of the vehicle door lock is identical to the front view shown in FIG. 1.

FIG. 2 is a left view thereof.

The right view of the vehicle door lock is identical to the left view shown in FIG. 2.

FIG. 3 is a top view thereof.

FIG. 4 is a bottom view thereof.

FIG. 5 is a perspective view thereof.

FIG. 6 is an open exploded perspective view from the left and front.

FIG. 7 is an open exploded perspective view from the top, right and front.

FIG. 8 is an open exploded right side view.

FIG. 9 is an open exploded perspective view from the top, rear, and right.

FIG. 10 is an open exploded left side view.

FIG. 11 is an open exploded perspective view from the bottom, left, and front; and,

FIG. 12 is an open exploded perspective view from the bottom, right, and rear.

The broken line showing of certain portions of the vehicle door lock is included for the purpose of illustration only and forms no part of the claimed design.
